INVENTOR.

Oliver T. Robertson

UNITED STATES PATENT OFFICE.

OLIVER T. ROBERTSON, OF MILFORD, OHIO.

COMBINATION HAND MOUTH-MIRROR AND CHIP-BLOWER AND FLUSHING AND SPRAYING DEVICE.

No. 838,648.

Specification of Letters Patent.

Patented Dec. 18, 1908.

Application No. November 19, 1904. Serial No. 238,522.

To all whom it may concern:

Be it known that I, OLIVER T. ROBERTSON, a citizen of the United States, and a resident of the village of Milford, in the county of Clermont and State of Ohio, have invented a certain new and useful Combination of Hand Mouth-Mirror and Chip-Blower and Flushing and Spraying Device, of which the following is a specification.

10 The several features of my invention and the various advantages resulting from their use conjointly or otherwise will be apparent from the following description and claims.

15 I will now proceed to describe my invention in detail.

In the accompanying drawings, making a part of this application, and in which similar letters of reference indicate corresponding parts, Figure 1 is a rear elevation of mechanism illustrating my invention. Fig. 2 is a side or edge elevation of the mechanism shown in Fig. 1, the blowpipe being moved to a different position. Fig. 3 is a front elevation of the same device. Fig. 4 is a front elevation of the mechanism illustrating my invention. Fig. 5 is a side or edge elevation of the devices shown in Fig. 4. Fig. 6 illustrates a single feature of my invention in side or edge view. Fig. 7 is a front elevation of the mechanism shown in Fig. 6.

20 A indicates a tube for conveying a fluid or fluids forward to the nozzle B. These fluids may be impelled forward through the tube A by any suitable means. Some of the well-known means for this purpose are a rubber bulb, such as W, or a pump with or without a valve, all of whose operations are well understood.

25 M indicates a mirror of a size suitable for insertion into the mouth. This hand mouth-mirror is located upon the tube A in the vicinity of the nozzle B. For convenience of attachment to a primary conduit and removal therefrom and also for the convenience of adjustment of the mirror the pipe A is divided into two sections A' and A'', and these two sections are adapted to be quickly united as one tube. A preferred mode of connecting them is indicated, and consists in 30 making one of the sections conically pointed and providing the other one with a conical orifice adapted to receive the conical point of the first-named section. For example, in Fig. 8, A'' is provided with a conical or tapering end A''' (shown in dotted lines,) while the section A' is provided with a conical or taper-

ing orifice A''. In practice the tapering point of section A' is inserted in the orifice A'', the two sections A' and A'' pressed together, and the union is complete. 60

A construction shown in Fig. 7, where the mirror is attached to a section A' and the nozzle B is inflexible, illustrates one feature of my invention; but my invention includes a much more perfect and a more highly-organized device than this. Such a device is shown in Figs. 1, 2, and 3. In these figures the tube-section A' is united to the nozzle by a joint, preferably a universal one, C. The fluid conveyed through section A' flows 65 through one or both of the arms C' of the section into the adjacent portion of the nozzle and thence out through the end B' of the nozzle. This universal joint enables me to move the point of the nozzle around anywhere in the line of the arc X (see Fig. 2) and also anywhere in the line of the arc Z. (See Fig. 3.) This arrangement enables me to locate the point of the nozzle most conveniently to be used at the same time that I am 70 enabled to place the mirror so as to examine in the best manner that portion of the tooth which is to be operated upon by the fluid passing through the nozzle B. 75

A device of more limited scope, but exceeding useful within limits, is the one shown in Fig. 5, where the joint between the nozzle B and the section A' is shown at C'. This joint is located behind the mirror. It enables the front end of the nozzle to be 80 turned around anywhere in the circular line Y, and thus adapts the nozzle to be used at many convenient points in connection with the mirror. 85

Where the device is to be used as a sprayer, 90 the delivery-tube will be divided into two parts, one for conveying the gas and the other for conveying a liquid. As the mode of introduction of the gas into one of these tubes and the liquid into the other of these 95 tubes is well known, further description thereof is omitted.

The great utility and value of my invention will be fully apparent to those engaged in the art of dentistry. Heretofore the mirror had to be held in the hand (usually the left) while the chip-blower when in use was held in the other. In excavating or grinding out decayed tissue of a tooth "chips" are formed, and the instrument used in forming 100 these is laid aside and the "chip-blower" is then taken up to dispel these chips or debris by 105 110

its action of blowing or flooding. Alternate repetitions of these operations were required until the chip blowing or flushing or spraying were no longer needed. My invention is especially advantageous in either blowing away dry chips by means of air or flushing by means of water. It is also advantageous in the dispelling of blood from the bleeding gums in operations upon them or upon the teeth. It is also of great value in the use of spray as an "occluding" means and in the treatment of diseased tissue. In all of these and other operations the hand-mirror will thus at the same time enable the dentist to inspect the tooth or gum at the point desired and to continually operate with his other hand.

When the construction is that shown in Figs. 1, 2, and 3, that end of the tube A which is adjacent to the nozzle is bent over in the form shown at A'. Such a formation of this part of the tube better enables the nozzle B to be adjusted so as to reach a desired portion of the tooth or gums at the same time that the hand-mirror is in full use.

Usually the mirror will be permanently connected to the fluid-delivery device; but in many cases it will be convenient to have the fluid-delivery device separate from the mirror, but capable of ready attachment thereto. One kind of means for making such ready attachment is illustrated in Fig. 7. There the ordinary handle M² of the mirror is shown and is connected to the tubes A and A' by the spring-clips M² M¹. Ordinarily, however, the ordinary handle of the mirror will be dispensed with and the tube which conveys the fluid is utilized as a handle. This latter construction is a very obvious economy and advantage also in the attainment of increased simplicity of construction.

Thus by my invention two operations can be carried on at the same time, one by each hand, and the mirror is also present, enabling

the resultant effect of both operations to be continually seen. The advantage of such possibilities in the more accurate execution of the work and in the large saving of time to the dentist and to the patient and the economy of nervous strain in the latter is obvious.

What I claim as new and of my invention, and desire to secure by Letters Patent, is—

1. In a dental instrument, the combination of a tube adapted to convey a fluid to a desired point, and a hand-mirror connected thereto, substantially as and for the purposes specified.

2. In a dental instrument, the combination of a tube-section A', provided with a nozzle B, and a mirror connected to the tube-section, and a tube-section A², the sections being constructed for ready and close union, substantially as and for the purposes specified.

3. In a dental instrument, the combination of the tube for delivering fluids, a mirror connected thereto, and a nozzle connected to the end of the tube and adapted to rotate in a plane substantially parallel to the plane of the mirror, substantially as and for the purposes specified.

4. In a dental instrument, the combination of a tube adapted to convey a fluid to a desired point, and a hand-mirror connected thereto, and means between the tube and its nozzle, for enabling the nozzle to be located at an angle to the length of the adjacent portion of the tube, substantially as and for the purposes specified.

In witness whereof I have set my hand to this specification in the presence of two subscribing witnesses.

OLIVER T. ROBERTSON.
